(57) **CLAIM**

The ornamental design for a sterilizer, as shown and described.

DESCRIPTION

FIG. 1 is the front view of the sterilizer according to the present invention.

FIG. 2 is the back view of the sterilizer according to the present invention.

FIG. 3 is a left side view of the sterilizer according to the present invention;

FIG. 4 is a right side view of the sterilizer according to the present invention;

FIG. 5 is a top view of the sterilizer according to the present invention;

FIG. 6 is a bottom view of the sterilizer according to the present invention; and

FIG. 7 is a perspective view of the front and right side of the sterilizer according to the present invention; and,

FIG. 8 is a perspective view of the front and left side of the sterilizer according to the present invention.
